S. C. SAMUELS

RAILROAD TRACK CONSTRUCTION

Filed March 12, 1923

UNITED STATES PATENT OFFICE.

SAMUEL COFFMAN SAMUELS, OF SAN FRANCISCO, CALIFORNIA.

RAILROAD-TRACK CONSTRUCTION.

Application filed March 12, 1923. Serial No. 624,350.

To all whom it may concern:

Be it known that I, SAMUEL COFFMAN SAMUELS, a citizen of the United States, residing at San Francisco, in the county of 5 San Francisco and State of California, have invented certain new and useful Improvements in Railroad-Track Constructions, of which the following is a specification.

My present invention relates to improvements in track constructions, which will be best understood from the following description and the annexed drawing of an illustrative embodiment, in which Fig. 1 is a vertical longitudinal section on the line 15—1 of Fig. 2 of a portion of a railroad tie, showing an illustrative form of my invention applied thereto. Fig. 2 is a plan view of Fig. 1, and Fig. 3 is a section on the line 3—3 of Fig. 2.

20 Like parts have like reference numbers in the several views.

In the form of my invention which I have chosen for purposes of illustration, the tie is formed of an upper portion 10 and a 25 lower portion 11 with the grain extending lengthwise of the tie and with the joint between the two sections also extending lengthwise of the tie and horizontal.

On the top of the tie is a rail plate 12 30 extending beyond the vertical edges of the tie and having integral portions 13—13 extending downward, parallel to the sides of the tie. On the bottom of the tie is a supporting plate 14 attached to the tie by bolts 15, which extend through the two plates and 35 through holes extending down the sides of the tie. The plate 12 may be formed with ridges 16—17 to locate the rail R, and the bolts 15 may be used to clamp the rail to 40 the plate 12 and the tie by means of members 18, beneath the heads of the bolts 15, the extended lip of each member 18 projecting over the flange of the rail as shown best in Fig. 1. The member 18 may be provided 45 with dowel pins 19 to prevent members 18 from turning.

The integral portions 13 are connected to the supporting plate 14 so as to prevent motion away from the vertical sides of the tie, and preferably this connection will also be formed so that the plates 12 and 14 may be moved relatively vertically, and as a means to this end, I have provided the integral members 13 with a plurality of projec-

tions 20 on the lower end of each of the 55 integral portions 13, which projections extend through corresponding openings in the plate 14, all of the projections 20 being of sufficient length to permit the plates 12 and 14 to approach each other before the solid portion of the integral portions 13 contact with the plate 14.

In order to transmit the weight and force applied to the rail R by the moving trains to the plate 14, I insert between the sides 65 of the tie and the integral portions 13, blocks 21 of wood, with the grain thereof vertical, these blocks being of sufficient length so that the weight on the plate 12 will be transmitted through the blocks 21 to the supporting plate 14. It will be understood that the plate 14 will rest on the ballast of the roadbed so that any weight transmitted through the blocks 21 will not be applied to the tie proper, and, therefore, that the tie proper 70 will be relieved of a corresponding amount of pressure which would otherwise tend to crush it. The plate 14 may be provided with projections 22 if desired.

It will be noted that the integral portions 80 13, by their connections to the top and bottom plates 12 and 14, and by their contact with the sides of the blocks 21, will bind the tie laterally to prevent its being crushed and forced out laterally. Preferably, when 85 the tie is made up of the two pieces 10 and 11, I will apply to the tie additional members to prevent the crushing of the tie, and to this end I may provide a plate 23 having downwardly projecting and integral portions 24 in contact with the sides of the tie, these integral members 24 extending through holes in a bottom plate which, in the 90 illustrative form, constitutes a portion of the supporting plate 14, though it will be understood that a separate plate may be provided for this purpose. A bolt 26 extends through the tie and through the plate 23 and the corresponding bottom plate.

When the rail R is on a curve it will be 100 subjected to horizontal pressure, as is well known, and I provide a means for holding the rail R anchored to resist this horizontal pressure and to prevent overturning of the rail. To this end I provide member 27 105 having, in the illustrative embodiment, an integral pivot 28 engaged in a hole in the rail plate 12 and having one end formed

to fit the side of the rail R, a boss 29 on either side of the member 27 being provided to give additional area. The end of the member 27 away from the rail engages, in 5 the illustrative form, the bolt 26, the member 27 being provided with a slot 30 adapted to permit the extended end 31 of the member 27 to swing into position beneath the nut on the bolt 26. A locking member 32 10 may be provided, this member having a hole through which the bolt 26 extends, and having a downwardly projecting portion 33 which extends over the edge of the extended portion 31 of the member 27. In addition, I may provide a recess 331 through 15 which a spike or the like may be driven into the tie to hold the member 27 in position.

In present practice, and as is well known, the constant blows of the moving train will 20 cause a crushing or wear in the tie beneath the track plate 12, and when this wear has proceeded sufficiently far, the tie is withdrawn and a new tie substituted for it, although a very considerable portion of the 25 discarded tie is not damaged. By my invention two of these discarded ties may be sawn longitudinally and the undamaged portions of the discarded ties be put together to form the portions 10 and 11, thereby saving one tie and by using the arrangement which I have described, these two portions may be held together to function as effectively as the original solid tie. The 30 metal members which surround the tie and carry the weight on the rail R will so distribute the load that the two-piece tie will have sufficient strength and moreover will be protected against the crushing blows delivered to the rail R. It will be understood, 35 however, that my arrangement may be applied to a solid tie.

It will also be understood that the arrangement which I have illustrated is merely one form of my invention and that 45 the embodiment thereof may be widely varied. It will also be understood that some parts of my invention may be used without other parts.

By using the relatively thin blocks 21 50 at either side of the tie, all or a great portion of the weight and the force of the blows on the rail R will be transmitted lengthwise of the grain of the wood, instead of crosswise thereof, as in the usual tie. 55 As is well known, wood has a much greater resistance to crushing when the force is applied endwise of the grain than when applied crosswise, so that, with my construction, there is little tendency for the wood to 60 be crushed or for the plate to be worn into the side of the tie.

By fitting the end of the member 27 beneath the head of the rail as well as against the side, the side thrust in the rail which 65 would tend to upset it, is more completely

resisted, such upsetting motion being transmitted directly to the plate 12 and furthermore being resisted by the other end of the member 27 through its connection to the tie.

By providing the form of connection between the plates 12 and 14, which I have described, it will be understood that the plate 12 may sink into the tie without interfering with the operation of the integral portions 13 and 24 to sustain the sides of the tie, the bolts 15 and 26 being tightened up as required, and the projections 20 and 25 sliding through the corresponding openings in the plate 14 to permit this adjustment.

The member 27 may be connected to the rail plate 12 in any of a number of ways and, if desired, may be made integral therewith.

I claim:—

1. In combination, a wooden tie, a rail plate extending crosswise of the top of the tie and beyond the side edges thereof, a supporting plate on the bottom of the tie and extending beyond the side edges of the tie and blocks of wood between the extended portions of said rail plate and said supporting plate, each block having its grain vertical and adapted to transmit pressure from the rail plate to the supporting plate.

2. In combination, a wooden tie formed in two parts with the joint extending lengthwise of the tie, a rail plate extending crosswise of the top of the tie and beyond the side edges thereof, a supporting plate on the bottom of the tie and extending beyond the side edges of the tie and blocks of wood between the extended portions of said rail plate and said supporting plate, each block having its grain vertical and adapted to transmit pressure from the rail plate to the supporting plate.

3. In combination, a wooden tie formed in two parts with the joint horizontal and extending lengthwise of the tie a rail plate extending crosswise of the top of the tie and beyond the side edges thereof, a supporting plate on the bottom of the tie and extending beyond the side edges of the tie and blocks of wood between the extended portions of said rail plate and said supporting plate, each block having its grain vertical and adapted to transmit pressure from the rail plate to the supporting plate.

4. In combination, a wooden tie, a rail plate extending crosswise of the top of the tie and beyond the side edges thereof, a supporting plate on the bottom of the tie and extending beyond the side edges of the tie and blocks of wood between the extended portions of said rail plate and said supporting plate, each block having its grain vertical and adapted to transmit pressure from the rail plate to the supporting plate, said rail plate having an integral portion extend-

ing outside said block and connected to said supporting plate to prevent sidewise motion of said integral portion.

5. In combination, a wooden tie, a rail plate extending crosswise of the top of the tie and beyond the side edges thereof, a supporting plate on the bottom of the tie and extending beyond the side edges of the tie and blocks of wood between the extended portions of said rail plate and said supporting plate, each block having its grain vertical and adapted to transmit pressure from the rail plate to the supporting plate, said rail plate having an integral portion extending outside said block and connected to said supporting plate to prevent sidewise motion of said integral portion, said connection being constructed and arranged to permit relative vertical motion between the plates.
- 10 6. In combination, a wooden tie formed in two parts with the joint horizontal and extending lengthwise of the tie and a metallic holding band about said tie, said band comprising a member having a top and two side pieces engaging respectively with the top and the sides of the tie and a second member connecting the two side pieces to prevent motion thereof away from the sides of the tie.
- 15 7. In combination, a wooden tie formed in two parts with the joint horizontal and ex-

tending lengthwise of the tie, and a metallic holding band about said tie, said band comprising a member having a top and two side pieces engaging respectively with the top and the sides of the tie and a bottom member connecting the two side pieces to prevent motion thereof away from the sides of the tie, said bottom member being freely movable vertically on said side pieces.

35 8. In combination, a tie, a rail plate thereon, a double-ended thrust member having at one end a pivotal connection with said plate, said connection being arranged to permit relative vertical motion between said member and said plate, and means to lock the other end of said member against motion.

40 9. In combination, a tie, a rail plate thereon, a double-ended thrust member pivotally connected thereto and having one end abutting the side of a rail on the plate, an abutment connected to the tie and means to connect the other end of the thrust member to said abutment.

45 10. In combination, a tie, a rail plate thereon, a double-ended thrust member having at one end an integral pivot engaging a recess in said plate and arranged to permit relative vertical motion between said member and said plate, and means to lock the other end of said member against motion.

50 55 60
SAMUEL COFFMAN SAMUELS.
